UNITED STATES PATENT OFFICE

ALFRED J. HIXON, OF BRAINTREE, MASSACHUSETTS

LIGHTING FIXTURE

Application filed March 18, 1930. Serial No. 436,755.

This invention relates to electric light fixtures of the bracket type and is designed to supply a novel and improved bracket having, among others, the advantages hereinafter claimed and described.

The bracket is especially adapted for use in hospitals and sick rooms where it is required for use under different conditions.

In the drawings of one form of my invention described and illustrated herein,

Fig. 1 is a front elevation;

Fig. 2, a side elevation with the housing in section;

Fig. 3, a vertical section on the line 3—3, Fig. 1, looking from the right;

Fig. 4, a cross-sectional detail in the direction of the arrow on the line 4—4, Fig. 2;

Fig. 5, a horizontal section on an enlarged scale on the line 5—5, Fig. 3; and

Fig. 6, an enlarged detail vertical section of the washer comprising part of the universal bracket mounting.

Referring first to Figs. 2, 3, my novel fixture comprises a housing 1 as of sheet metal, adapted to be set into the wall of the room and provided with a front cover plate 2 secured to the frame *a* by screws 3.

Within the housing 1 is a rectangular frame *a* comprising top and bottom members 4, 5 respectively, connected by upright corner members 6. The front members 6, Figs. 2, 3, 4, have flanges 7 through which extend the screws 8 into the housing.

Between the top and bottom plates 4, 5, Figs. 2, 3, 4, extends, one on each side, a rail 9, on which travels a carriage 10, which carries a reel 11 for the current cord or wire 12, and the bracket 13. This bracket, Fig. 3, has a reduced end 15 which fits snugly passage 16 in a ball 17 held movably against its seat on the end of an outwardly extended neck 18 of the carriage casting 10, by a threaded ring 19. This ring permits free universal movement of the ball 17 on its seat without loosening the ring, through the presence of a washer 20 locked to the neck 18 by said ring 19 and by two pins 21 on the neck entering holes therefor in the washer 20.

50 The carriage 10, Fig. 4, has a vertical rib or

flange 22 on each side which travels in a groove 23 in the rail 9.

The reel 11, Figs. 2, 3, 4, is mounted on an axle 25 in the carriage 10 and is provided interiorly with a coiled spring, not shown, for automatically winding up the cord 12 thereon. The cord 12 from the socket 28 on the bracket or arm 13 is carried through the ball 17 and wound upon the reel 11 and connected thereto to include it in the circuit. 60 From the terminals 26, Fig. 4, on the carriage 10 extend forked finger contact members 27 inwardly and on either side of the shaft 25 and against the ends of the reel 11. From the insulated terminals 26, Figs. 4, 5, on the carriage 10, cords 30, shown broken away, 65 run to terminals 31, 32 on the top member 4.

From the terminals 31, 33, run the power lines 34, 35, to any suitable source of supply, as a convenient socket in the wall, not shown. 70 For convenient operative control, Fig. 5, lines 36, 37 run from the terminals 32, 33, to a switch 37, Figs. 1, 2, 3, on the bar 38 of the frame and extending through the front plate 2. 75

The inner faces of the corner members 6, and top and bottom members 4, 5, are grooved at 39, Figs. 3, 4, to receive a flexible strip of metal or other suitable material 40 through which the neck 18 of the carriage 10 extends, 80 the strip acting to form a cover for the opening in the front plate 2 at all times by sliding in its groove as the carriage 10 and its neck 18 is moved up or down.

For use the housing is installed in the side 85 wall of the room at such height that the bracket or arm 13 will support the light bulb conveniently for use.

Of course further adjustment of the bracket can be made either up or down as 90 desired. If more convenient, as for moving it around in the room, the arm 13 may be rendered portable and may be withdrawn from its ball socket 17 and the cord unreeled to such length as desired, dotted lines, Fig. 2. 95

The arm may be locked in any desired angular position in the ball 17 by turning up the ring 19 on the neck 18. The cord 30 allows the carriage 10 to be raised or lowered 100 as desired. The free movement of the ball

17 permits the cord 12 to unwind or wind itself up smoothly on the reel 24 as the latter rotates.

The carriage 10 being mounted on the rear corner members 6, a firm support is provided, all weight of the carriage is borne by said rear members with no tendency to spring the front of the frame outwardly. The reel moving with the carriage there is but little slack permitted in the cord 12.

10 The foregoing described fixture is particularly useful in hospitals and sick rooms for children and those suffering from nervous troubles. Such invalids are very temperamental and prone to seek and find anything in the room that can be moved or played with. They remove the bulbs, try to turn or move the brackets and cut the cords. Aside from the possible serious results that may follow such handling of the fixtures, etc., the inconvenience arising from minor troubles is an 15 annoying.

By the use of such a fixture as described, the cord is hidden from view when not in use, the fixture may be placed sufficiently high on the wall to be normally beyond reach of the patient and yet accessible to the nurse or attendant.

20 It is sanitary and it offers little opportunity for dust to collect on the cord and later to be scattered in the room.

25 My invention is not restricted to the particular embodiment thereof described and illustrated.

30 Claims:

1. A lamp wall flush lighting fixture comprising a frame adapted to be seated in a wall pocket, a cover for the frame and pocket including a panel slidable in the frame, with a lamp carrying bracket universally adjustable on the panel, and an automatic cord winding reel movable in the frame, and carrying a flexible current cord secured thereto and to said frame and the bracket.

45 2. A lamp wall flush lighting fixture comprising a frame adapted to be seated in a wall pocket, a cover therefor including a slidable panel with a universally mounted lamp bracket thereon, with an elongated opening therein to permit adjustment of the bracket, a reel carriage slidable in the frame and carrying an automatically operative winding reel, and a switch on the frame connected in circuit with the bracket and carriage.

50 3. In a wall flush lamp fixture with a portable bracket adapted to be seated in a wall to conceal the cord, a frame, and a carriage slidable thereon carrying a cord winding reel, said carriage carrying a pocket covering panel also slidable in the frame, and a universally movable and portable lamp bracket thereon.

55 4. In a wall enclosed lamp fixture a frame, a cord carrying reel, and a carriage for said reel slidable thereon and having a neck ex-

tended through said frame and a universally mounted bracket thereon, including a socket on the neck member, a ball therein, a locking washer nonrotatable on the socket and a locking ring threaded to the neck over the washer.

60 5. The combination with a wall having a pocket therein of a housing, a bracket carrying frame within the housing, a carriage movable on the frame with a cord carrying reel, a pocket closing panel carried by the carriage and a bracket member extended through the panel and movably mounted on the carriage and extensible therefrom.

65 In testimony whereof, I have signed my name to this specification.

ALFRED J. HIXON.
